METHOD AND APPARATUS FOR THE MANUFACTURE OF DIPPED RUBBER GOODS

John M. Auzin, Warwick, R. I., assignor to Davol Rubber Company, a corporation of Rhode Island

Application July 2, 1945, Serial No. 602,873

2 Claims. (Cl. 18—47.5)

1

The present invention relates to the manufacture of rubber articles, and has particular reference to the manufacture of pessaries and the like by dipping.

The principal object of the invention is to provide a novel arrangement for facilitating the formation of a roll edge on a pessary or the like.

Another object of the invention is to provide a novel arrangement which simplifies the rolling of the edge around a resilient core.

With the above and other objects and advantageous features in view, the invention consists of a novel form and a novel procedure for obtaining a roll edge on a pessary or the like in a simple and effective manner, more fully disclosed in the detailed description following, in conjunction with the accompanying drawings.

In the drawings:

Fig. 1 is a front elevation of a pessary having a roll edge formed in accordance with the invention;

Fig. 2 is a section on the line 2—2 of Fig. 1;

Fig. 3 is a perspective view of the novel form for dipping, a resilient coil spring being shown in position for forming the core; and

Fig. 4 is a vertical section through the mold, after dipping, with the roll edge partly formed.

The manufacture of pessaries and similar articles having roll or bead edges normally is accomplished by dipping a suitable form in natural or synthetic rubber in solution, such as latex, to provide the body of the article and an elongated skirt, placing a resilient core such as a coil spring over the lower edge of the skirt, and then rolling up the resilient core in the skirt so as to embed the core in the rolled up material and form a roll edge or bead. It has been found that a form of uniform diameter, such as is commonly used, causes the tension of the resilient core to increase as the roll edge builds up, and that the skirt, if in moist condition, will slide up and buckle ahead of the spring coil unless the tension is released. It has also been found that it is advantageous to form the roll edge when the skirt is in moist condition, as the bond between the resilient core and the enveloping material is firmer and a higher production results; whereas the formation of a roll edge after thorough drying of the rubber material requires time and additional handling, as well as reducing the strength of the bond.

I have therefore found it advisable to provide a form which has the usual pessary shape, for example, at the dipping end, and which has a

2

tapered lead towards the dipping end, this tapered lead increasing in diameter just below the usual pessary roll edge groove, so that the resilient core, which is initially slightly distended, first gradually decreases in diameter and then momentarily increases in diameter before entering the roll edge groove. The tapered lead facilitates the rolling process and eliminates sliding back of the skirt, and the slight expansion before the roll edge groove is reached equalizes the tension in the core and smooths out the formed roll edges so that the roll edge, when within the groove, is of uniform tension, and is symmetrical and smooth in shape, whereby the finished articles are uniform in shape, and dry and cure without distortion.

Referring to the drawings, the pessary 10 includes a flexible dome 11 and a roll edge 12 in which a resilient core 13, preferably a spiral wire coil, is embedded. A special form 14, see Fig. 3, is used for dipping, the form having a dome top 15, a roll edge groove 16, and a body portion 17. The body portion has a lower groove 18 in which the resilient core is initially placed, and a tapered central portion 19 which is marked or scored, as indicated at 20, to disclose the dipping depth, this depth being about 1½ inches for a 75 mm. pessary and about 1¼ inches for a smaller pessary. The tapered central portion 19 is initially of greater diameter than the roll edge groove, as indicated at 21, then tapers down almost to the diameter of the roll edge groove, as indicated at 22, then abruptly enlarges, as indicated at 23 when closely adjacent the roll edge groove 16, to form a slight circumferential hump or ridge 24. The initial out taper should be about ½ inch, and the slope-in should be about 2¾ inches.

The form 14 is first dipped in latex or other rubber solution to the line 20, to obtain an elastic layer 25 having a depending skirt 25a, see Fig. 4, the thickness of layer found suitable being about .012 inch. The coil spring 13 is already in position in the groove 18, see Fig. 3, and is readily moved out of the groove and over the tapered central position 19, as the taper causes it to smoothly roll down, this smooth rolling down being facilitated and aided by the natural contraction of the coil spring, which is initially under slight tension when it passes over the enlarged region 21. As the coil spring advances, aided by its contraction, it engages the lower edge of the skirt 25a, which rolls up also as shown in Fig. 4, until the reduced diameter region 22 is reached, this region being preferably of slightly

smaller diameter than the core; at this point the coil spring is under very little tension, the strain is equalized and becomes uniform, and the partly formed roll edge smooths out. When the partly formed roll edge 26 is pushed over the hump or ridge 24 the spring coil is again under increased tension so that it clicks into the groove, which is small enough so that the resilient core becomes free of tension; any strain resulting from the initial rolling has become equalized, and the hump thus serves to uniformly distribute the coil spring and the rolled up skirt so that the roll edge or bead which seats within the groove 16 is uniform in size and is uniform in tension. The manufacture is completed by drying and curing; since the roll edge core is free when in the form groove it becomes under adjusting tension when the pessary is cured.

The novel method, by using the novel form, thus produces a uniformly satisfactory product, as the resilient core is first stretched, then its tension is released to become equalized, and the formed roll edge is sharply momentarily stretched to obtain a close and uniform join between the rolled up skirt material and the resilient core parts. Although a wood form is suitable, a porcelain form may be used, suitably marked to show the dipping depth.

Although I have described a specific form and a specific procedure suitable for the manufacture of roll edge or beaded pessaries, it is obvious that other articles of rubber or the like having roll edges or beads may be made, the forms being designed to correspond to the size and shape of the desired article.

I claim:

1. The method of forming an article having a

roll edge containing a resilient core, comprising the steps of dipping a generally cylindrical form in rubber solution to deposit a layer thereon having a skirt, positioning a resilient circular core under tension over the edge of the skirt to become embedded in the skirt material, and forming a bead by rolling the skirt edge and the resilient core over the deposited layer, first gradually releasing the tension of the core during the rolling operation, then momentarily sharply increasing the core tension, and finally reducing the core tension at the completion of the rolling operation.

2. A generally cylindrical form for dipping rubber and rubber material articles having a roll edge or bead, comprising an upper dome end shaped to conform to the article, the body of the form being reduced in diameter to provide a narrow annular groove below the dome end, then being increased in diameter and again reduced in diameter to provide a narrow hump just below the groove, and then being gradually increased to a larger diameter than the diameter of the groove to provide an elongated skirt dipping portion, the elongated portion having a terminal annular groove at its lower end.
